(57) **CLAIM**

The ornamental design for a filling machine as shown and described.

DESCRIPTION

1.1 is a front view of a first embodiment of a filling machine, showing our new design;

1.2 is a top plan view thereof;

1.3 is a right side view thereof;

1.4 is a left side view thereof;

1.5 is a rear view thereof;

1.6 is a bottom plan view thereof;

2.1 is a front view of a second embodiment of a filling machine, showing our new design;

2.2 is a top plan view thereof;

2.3 is a right side view thereof;

2.4 is a left side view thereof;

2.5 is a rear view thereof; and

2.6 is a bottom plan view thereof.

The broken lines in the figures illustrate portions of the filling machine that form no part of the claimed design.

1 Claim, 12 Drawing Sheets
